UNITED STATES PATENT OFFICE

EDWARD M. CLAYTOR, OF WILKINSBURG, PENNSYLVANIA, ASSIGNOR TO WESTINGHOUSE ELECTRIC & MANUFACTURING COMPANY, A CORPORATION OF PENNSYLVANIA

THERMAL RELAY

Application filed June 24, 1927. Serial No. 201,055.

My invention relates to protective devices and particularly to thermal relays.

An object of my invention is to provide a relay that shall be simple in construction and easily manufactured.

Another object of my invention is to provide a thermal relay that shall depend for its operation upon the change of magnetic properties in its thermal element.

10 A further object of my invention is to provide a thermal relay that shall be re-set automatically.

15 And a further object of my invention is to provide automatic re-setting means for a thermal relay that shall be operable to permit the relay to operate only when a circuit-controlling device associated therewith is in a predetermined circuit-controlling position.

20 In practicing my invention, a circuit-controlling device, or an electric switch, is provided for controlling such energy-translating devices as electric motors, etc. In order that the translating devices may be protected against overloads, a thermal relay is provided for causing the switch to be actuated to a circuit-breaking position upon the occurrence of an overload of predetermined value.

25 Means are provided also for re-setting the relay the moment the switch has been actuated to a circuit-breaking position which means are effective to hold the relay in its re-set position until the thermal element has returned to its normal operating position. The re-setting means cooperates with the switch in such manner that the relay is free to drop out whenever the condition of the thermal element is of a predetermined value, provided the switch is in a closed or circuit-making position.

30 For a fuller understanding of my invention, reference may be had to the following description, taken in conjunction with the accompanying drawings, in which

45 Figure 1 is a view, in side elevation, of a

circuit-controlling device embodying my invention and

Fig. 2 is a view, in front elevation, of the same device.

Fig. 3 is a view, in section, taken on line 50 III—III of the device illustrated in Fig. 1 and

Fig. 4 is a schematic illustration of circuits and apparatus embodying my invention.

55 In the drawings, a panel or base 10 of insulating material is illustrated on which is mounted a stationary terminal 11. At the outer end of the terminal 11 is secured a contact tip 12, of substantially L-shape, by means of a bolt 13. The contact tip 12 constitutes the stationary member or contact of a main circuit interrupter.

60 Beneath the terminal 11, a core frame 14 is located and is secured to the panel 10 by means of a bolt 15 passing through the panel 10 and terminating in the core frame 14 with which it has screw-thread engagement. The frame 14 may be made of iron or other suitable magnetic material, and, as illustrated, is in the form of a bracket of substantially 65 L-shape. The portion of the frame 14 extending laterally from the panel 10 is provided with a pair of spaced-apart portions 16 and 17 between which an armature 18 is located. The armature 18 may be made of 70 iron or other suitable magnetic material, and may be secured to the frame 14 by a hinge pin 19 that passes through the frame and the armature. The hinge pin is provided, at opposite ends, with spring clips 21 which 75 prevent the same from sliding out of position, as will be readily understood by referring to Fig. 2 of the drawing.

80 The upper end of the armature 18 is provided with spaced-apart lugs 22 between 85 which a movable contact support 23 is located, the support 23 being hinged thereon by a hinge bolt 24 that passes through the lugs and the support. A contact tip 25 is secured to the outer end of the support 23 by 90

a bolt 26. The tip 25 may be of substantially L-shape and similar in construction to the tip 12.

The adjacent faces of the tips 12 and 25 may be slightly circular in order that a rolling contact may be effected therebetween when the contacts are actuated into and out of engagement with each other.

In order that rolling contact between adjacent faces of the tips 12 and 25 may be effected, a spring 27 is located between the lower face of the contact support 23 and a shoulder portion 28 of the armature. The spring may be maintained in this position by lugs 29 and 30 that extend into the ends of the spring 27, the lugs being secured to, or made integral with, the movable support 23 and the armature 18, respectively.

So that the distance between contact tips 12 and 25 may be adjusted to any desired value, when the contacts are in a disengaged position, a tail piece 32 is provided as an integral part of the armature 18 at the end of which is mounted an adjusting screw 33. When the armature swings outwardly on the hinge pin 19, the upper end of the adjusting screw 33 engages the frame 14, thus limiting the turning movement of the armature 18 on the hinge pin.

In order that the armature 18 may be free from current-carrying duty, a shunt 35 is provided. As shown, the ends of the shunt may be secured in a clip 36 attached to one of the lugs 22 and a clip 37 that is secured to the armature near the panel 10. Thus, it is seen that, when the contact tips 12 and 25 are in the positions shown in Fig. 1, a circuit is completed from the terminal support 11 through the contact tips and the shunt 35 to the bolt 15.

The armature 18 may be actuated to the position shown in Fig. 1 and held in this position by means of a magnet coil 39. As shown, the coil is held against the portion of the core frame 14 adjacent to the panel 10 by means of a plate 41 that is secured to a lug 42 on the armature frame by a screw 43. The coil 39 is provided with a core 44 that passes through the coil, the outer end of which engages the upper end of armature 18 and the inner end of which rests against the core frame 14. The core may be secured in this position by a bolt 45 that extends through the panel and into the tapped end of the core with which it has screw-thread engagement.

The coil 39 is provided with terminals 46 and 47 which may be connected to a suitable source of electrical energy.

When the coil 39 is energized, the armature 18 is actuated to the position shown in the drawings. However, if the coil is de-energized, the armature swings outwardly to effect disengagement between the contact tips 12 and 25. In order to accelerate the out-

ward movement of the armature, a spring 48 is provided that presses against the lower end of the plate 41 and the outer edge of the armature 18.

When the circuit interrupter, constituted by the contact tips 12 and 25, is in the position shown in the drawings, and the magnet coil is energized, a permanent energizing circuit may be established through the coil by means of an interlock 49. The interlock 49 comprises a bell-crank lever 51 that is pivotally mounted on a bracket 52. As shown, the upper end of the bell-crank lever 51 engages a bar 53 secured to the tail piece 32. The lower end of the bell-crank lever has a contact bridging member 54 secured thereto to bridge a pair of stationary contacts 55, which are included in the circuit of the magnet coil.

In order that the bell-crank lever 51 may swing to such position that the bridging member 54 shall be disengaged from the stationary contacts 55 when the armature contact 18 is in a position to cause disengagement between contact tips 12 and 25, a spring 56 is provided and, as shown, is located between the bracket 52 and the lower portion of the bell crank lever 51.

In order that the coil 39 may be de-energized to effect a release of the armature 18 to the position in which the switch contacts controlled thereby are actuated to a circuit-breaking position when a current of a predetermined value has traversed the same for a predetermined length of time, a thermal relay 58 is provided. As shown, the relay 58 is provided with a bracket 59 of substantially U-shape that is secured to the panel 10 by means of studs 61 and 62. To the upper portion of the bracket 59 that extends laterally from the panel, a magnet 63 of substantially horse-shoe shape is secured by means of a plate 64, that extends laterally across the face of the magnet, and a screw 65 that has screw-thread engagement with the bracket 59.

The bracket 59 and the plate 64 may preferably be of non-magnetic material and may be made, by a simple stamping operation, from a sheet of metal. To the lower horizontally extending portion of the bracket 59, a moveable contact-carrying member 66 is secured by means of a hinge pin 67.

The member 66 may be made by a simple stamping operation from a sheet of non-magnetic material. As shown, the edges of the lower end of the member 66 are upturned, the upturned edges being provided with alined slots 68 with which a link 69 may have sliding engagement.

A contact-bridging member 71 is insulately secured to the member 66 by a clip 72 which may be attached to the member 66 by a rivet or any other suitable means. To the upper end of the member 66 an inductor or magnetic member 73 is secured by rivets or

other suitable means, the inductor comprising upwardly extending members 74 and 75. As shown, the members 74 and 75 are positioned adjacent to the poles 77 and 78 of the magnet.

When the contact-supporting member 66 is in the position shown in the drawings, the portions 74 and 75 of the inductor 73 engage a reversibly magnetic member 79 that is electrically connected to, and supported by, a pair of studs 81 and 82 preferably of non-magnetic material. As shown, the studs are provided with screw-threaded end portions which pass through the base or panel 10, the end portions being provided with nuts 83 by means of which the studs may be held securely on the base.

The member 79 may be made of a nickel-steel alloy containing approximately 35% iron, 65% nickel with minor percentages of other elements, as desired. The characteristic of this alloy is such that, when heated to a temperature of approximately 150° C., it becomes non-magnetic and, when cooled to a temperature slightly below this temperature, it again becomes magnetic. For this reason, the member 79 may be termed a reversibly magnetic member; that is, when normally cool, it is magnetic; when heated to a predetermined temperature, it becomes non-magnetic and if permitted to cool below this temperature, it again becomes magnetic.

When the inductor 73 engages the reversibly magnetic member 79, a magnetic path is established from the pole 77, through the inductor 74, the member 79 and the inductor 75, to the pole 78. However, if the member 79 becomes non-magnetic, the magnetic path is broken and the member 66 is caused to swing outwardly, thereby actuating the inductor 73 away from the poles of the magnet.

At the same time, the contact-bridging member is also moved outwardly from the position shown in Fig. 1 of the drawing.

In order that the circuit of the magnet coil 39 shall be broken, when the contact-bridging member 71 has moved outwardly upon release of the inductor 73 from the member 79, a pair of resilient contact members 85 and 86 are provided. These contacts may be yieldingly supported at the ends of the studs 61 and 62 by means of bolts 87 and springs 88, it being understood that the studs 61 and 62 are in circuit with the magnetic coil 39.

In order that the contact-bridging member 71 may be actuated into engagement with the resilient contacts 85 and 86 the moment the armature 18 is actuated to a position in which the contact tips 12 and 25 are disengaged, a push rod 89 is provided. As shown, the push rod moves vertically through apertures 91 and 92 in the horizontally extending portions of the bracket 59. The link 69 is pivotally secured to the push rod 89 and is

adapted to be moved vertically thereby. The push rod 89 may be actuated upwardly by a spring 93 that is located between the lower horizontally extending portion of the bracket 59 and a stop-member 94 attached to the push rod.

The upper end of the push rod is provided with an adjustable head 95 which engages the bar 53 carried by the tail piece 32. When the armature 18 is in the position shown in Fig. 1 of the drawings, the push rod 89 is held in such position that the spring 93 is maintained in compression. Therefore, when the armature 18 swings outwardly and the tail piece 32 upwardly, the push rod 89 is actuated upwardly by the spring, thereby causing the link 69 to engage the member 66 and to actuate it to the position shown in Fig. 1. The portions 74 and 75 of the inductor 73 are, therefore, caused to engage the reversibly magnetic member 79 and the contact-bridging member 71 to re-engage the stationary contacts 85 and 86.

If the armature 18 is in the position shown in Fig. 1 and the member 79 is heated to the temperature at which it is rendered non-magnetic, the member 66 will be actuated downwardly by gravity to effect the de-energization of the magnet coil 39 and a consequent opening of the switch contacts 12 and 25. Therefore, it is seen that the main circuit interrupter cannot be maintained in a circuit-making position until the member 79 has cooled to a temperature at which it becomes magnetic.

It is to be understood that the member 79 may be made in various sizes and shapes, depending upon the thermal characteristics desired. That is, if the relay is to operate to de-energize the coil 39 when a relatively small current traverses the main circuit interrupter, the thermal capacity of the member 79 should be relatively small and the resistance relatively high. If the relay is to operate at a higher value of current, the thermal capacity of the member 79 may be made greater and the resistance less.

In Fig. 4 of the drawings, an application of the device illustrated in Figs. 1 to 3 inclusive, is illustrated. As there shown, a motor 97 having a shunt field winding 98 is connected for energization between supply conductors 99 and 101. The motor may be energized by pushing a starting switch 102 to the position illustrated by the broken lines, thereby effecting energization of the magnet coil 39, the energizing circuit being from supply conductor 99 to the starting switch 102 a stopping switch 103 and the bridging contact member 71 to the supply conductor 101. When the coil 39 is energized, the contact tip 25 engages the contact tip 12, as shown by the broken lines, and the motor is then connected to the supply conductors 99 and 101.

As shown, the magnetically reversible member 79 is connected in series with the motor 97. When the main circuit interrupter has been closed by the magnet coil 39, the contact bridging member 54 engages the stationary contacts 55, thus establishing a permanent energizing circuit through the magnet coil 39. The starting switch 102 may now be released to its full-line position.

If a current of a predetermined value has traversed the motor for a predetermined length of time, the member 79 will be heated to such temperature that it will no longer be magnetic. When such condition occurs, the contact-bridging member 71 is released to the broken-line position shown in Fig. 4, and the energizing circuit of the magnet coil 39 is broken, thereby effecting disengagement of the contact members 12 and 25 and de-energization of the motor.

The moment the motor is de-energized by the opening of the contact members 12 and 25, the spring 93 becomes effective to actuate the contact-bridging member 71 and the inductor 73 to the positions shown in Figs. 1 and 2. Thus, if the energizing circuit of the coil 39 is again established before the member 79 becomes magnetic, the contact-bridging member will be released to its circuit breaking position to again effect de-energization of the coil 39.

By my invention, I have provided a magnetic thermal relay for controlling the operation of a main circuit interrupter whereby the temperature of a motor or other electrical-energy-translating device may be limited to a safe value.

I have provided also, a relay that is automatically reset to its operative position whenever the circuit interrupter controlled thereby has been actuated to a circuit breaking position. However, the automatic resetting device is so constructed that the relay is permitted to drop out or to open a circuit when the thermal condition of the relay is above a predetermined value.

Various modifications may be made in the device embodied in my invention without departing from the spirit and scope thereof. I desire, therefore, that only such limitations shall be placed thereon as are imposed by the prior art and the appended claims.

I claim as my invention:

1. A thermal relay comprising a support, a magnet carried thereby, a reversibly magnetic member, a movable member carried by said support, and an inductor carried by the movable member, said inductor being magnetically secured to said reversibly magnetic member by the magnetizing effect of said magnet.

2. A magnetic thermal relay comprising a support, a permanent magnet carried thereby, a movable member, a reversibly magnetic member an inductor carried by said movable

member for providing a magnetic circuit through the reversibly magnetic member and the magnet, and means for effecting movement of said movable member in response to a change in the magnetic properties of said reversibly magnetic member.

3. A magnetic thermal relay comprising a magnetically reversible member, a movable member, an inductor carried thereby for normally engaging said magnetically reversible member, and means for establishing a magnetic circuit through said inductor and reversibly magnetic member when in engagement.

4. The combination with a main circuit interrupter and a magnet coil for actuating said interrupter to a circuit-making position upon the energization of said coil, of a thermostatic device for controlling the energization of said magnet coil, said device comprising a magnetically reversible member, means for heating said member in accordance with the current traversing the circuit interrupter, a movable magnetizable member for engaging said magnetically reversible member when normally cool and for releasing the same when heated to a predetermined temperature, a permanent magnet for magnetizing said magnetizable member, and a circuit interrupter actuatable by said magnetizable member for de-energizing said magnet coil upon the occurrence of said temperature.

5. The combination with a main circuit interrupter for controlling a translating device, and a thermal relay for controlling the main interrupter, of a lost-motion mechanism for biasing said relay to one circuit-controlling position only when the main interrupter is in a predetermined circuit-controlling position.

6. In combination, a magnetically reversible member, a movable member, an inductor carried by the movable member, a permanent magnet for magnetizing said inductor when the inductor engages the magnetically reversible member, means for heating said reversible member to a temperature of a predetermined value and means for effecting movement of said movable member when said temperature is reached.

7. In combination, a main switch having movable contact mechanism for controlling a translating device, a thermally-responsive switch having movable contact mechanism, spring-actuated means for holding said thermally responsive switch in one position when the main switch is in an open position, and means actuatable by said main switch for holding the spring-actuated means out of engagement with the thermally responsive switch when the main switch is closed, whereby the movable contact mechanism of the thermal switch may be actuated to a circuit-breaking position when the main switch is in a closed position.

8. The combination with a main circuit interrupter for controlling a translating device and a thermal relay for controlling the main interrupter, of a resilient means having a lost motion connection with the relay for biasing it to a predetermined circuit-controlling position when the main interrupter is in a predetermined circuit controlling position.

10 In testimony whereof, I have hereunto subscribed my name this 16th day of June, 1927.

EDWARD M. CLAYTOR.
